United States Patent Office

Des. 192,942
Patented May 29, 1962

192,942

DECANTER

Ernest L. Du Pree, New York, N.Y., assignor to Schenley
Industries, Inc., New York, N.Y., a corporation of Delaware

Filed Aug. 18, 1961, Ser. No. 66,421

Term of patent 14 years

(Cl. D58—6)

FIGURES 5, 6 and 7 are sectional views through the front face only of the decanter and are taken on the lines 5-5, 6-6 and 7-7, respectively, of FIGURE 1.

I claim:

The ornamental design for a decanter, as shown and described.
